UNITED STATES PATENT OFFICE.

JAMES HARDEN SLAWSON, OF NORTON, INDIAN TERRITORY, ASSIGNOR
OF ONE-HALF TO WILLIAM F. SLAWSON, OF NORTON, INDIAN TERRITORY.

BRIDLE-BIT.

SPECIFICATION forming part of Letters Patent No. 773,601, dated November 1, 1904.

Application filed January 11, 1904. Serial No. 188,641. (No model.)

To all whom it may concern:

Be it known that I, JAMES HARDEN SLAWSON, a citizen of the United States, residing at Norton, in the Chickasaw Nation, Indian Territory, have invented a new and useful Bridle-Bit, of which the following is a specification.

This invention relates to improved bridle-bits, and has for its object to improve and cheapen the structure and increase the strength of such devices; and the invention consists in certain novel features of construction, as hereinafter shown and described, and specified in the claims.

In the drawings illustrative of the invention, in which corresponding parts are denoted by like designating characters, Figure 1 is a perspective view of the improved device. Fig. 2 is a side elevation, partially in section, of one of the side members of the improved device.

The improved bridle-bit consists of two spaced cheek members transversely connected by a bit member and with or without a connecting-bar at their lower ends, and as the cheek members are precisely alike corresponding reference characters are employed for like parts in each. The cheek members are each formed of a single piece of wire of suitable gage to withstand the strains to which they will be subjected and bent into elongated loops with parallel spaced sides 10 11 and preferably circular upper ends 12, with one side, as 10, extended at the lower end and terminating in an eye 13 and with the other side bent laterally and looped around the side 10 above its eye 13, as shown at 14. The sides 10 11 are connected by coupling members 15, preferably cast thereon, as illustrated in Fig. 2, the side members 10 11 being fully embedded in the coupling members at the ends and centrally thereof and only partially embedded at other points, as shown. By this means the coupling members are lightened materially without reduction of their strength or holding power upon the cheek members.

Connecting the coupling members 15 is a bar member which forms the bit proper of the device and is preferably formed of two rods 16 17, closely associated and cast by their ends in the members 15 and with the rod 16 bent centrally into a curb-loop 18. The lower

extended ends of the sides 10 may also be connected by a transverse brace-bar 19, looped by its ends thereto between the eyes 13 and loop connections 14, as shown. The cheek- 55 straps of the bridle (represented at 20 21) will be connected in the ordinary manner to the rings 12, and the driving-reins will be connected, as at 22 23, to the eyes 13.

By this simple means a very strong, durable, and rigid bridle-bit structure is produced which may be cheaply manufactured and applied to any bridle or head-stall in common use.

The material employed for the cheek members and the bit and cross-bar portions will preferably be steel of the required size, and the coupling members may be of iron, brass, or other metal or metallic compounds and plated, galvanized, or otherwise protected or 70 ornamented.

The parts may be of any desired size and of any fanciful design and may be otherwise modified in minor particulars without departing from the principle of the invention or sacrificing any of its advantages.

Having thus described the invention, what is claimed is—

1. A bridle-bit embodying two cheek members, each comprising a loop and a pair of spaced parallel arms, a double bit-bar one of which is provided with a curb, and coupling members cast around the arms and the terminals of the bit-bar.

2. A bridle-bit embodying two cheek members, each comprising a loop and a pair of spaced parallel arms, one of the arms terminating at its lower end in an eye, and the other in an angular offset terminating in a loop to embrace the arm above the eye, a 80 brace-bar having its terminals looped around the two longer arms adjacent to the eye, a bit-bar, and coupling members cast around the arms throughout a portion of their length and the terminals of the bit-bar.

In testimony that I claim the foregoing as my own I have hereto affixed my signature in the presence of two witnesses.

JAMES HARDEN SLAWSON.
